[57] CLAIM

The ornamental design for a compact disc cleaner, as shown and described.

DESCRIPTION

FIG. 1 is a top perspective view of a compact disc cleaner showing my design, in which a cover of said compact disc cleaner is opened;

FIG. 2 is a top perspective view thereof with said cover being closed;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side elevational view thereof; and,

FIG. 8 is a right side elevational view thereof.
